UNITED STATES PATENT OFFICE.

JOHN W. HUNGAD, OF ROCHESTER, NEW YORK.

BLACKBOARD ATTACHMENT.

SPECIFICATION forming part of Letters Patent No. 466,606, dated January 5, 1892.

Application filed March 3, 1891. Serial No. 383,647. (No model.)

To all whom it may concern:

Be it known that I, JOHN W. HUNGAD, of Rochester, in the county of Monroe and State of New York, have invented a certain new and useful Improvement in Blackboard Attachments; and I do hereby declare that the following is a full, clear, and exact description of the same, reference being had to the drawings accompanying this specification.

10 This invention relates to devices attached to the bottom of blackboards for the purpose of cleaning the erasers and holding the crayons; and it consists in the combination of a set of parallel strained wires on which the eraser can be cleaned, and a carrier provided with tubular bearings which embrace all the wires, said carrier serving the double purpose of holding the crayons, being movable from end to end of the wires, and of cleaning the wires 15 of chalk-dust, all as hereinafter described.

15 In the drawings, Figure 1 is a perspective view of the lower portion of a blackboard with my improvement attached. Fig. 2 is a cross-section of the board and a plan view of the attachment. Fig. 3 is an enlarged cross-section. Fig. 4 is an elevation showing the straining device for the wires.

20 A indicates an ordinary blackboard, provided at its bottom with a ledge B for catching the chalk-dust. C is the rack erected on this ledge. It consists of three parallel wires a a a, attached to bearings b b b, screwed fast to the ledge, the wires resting some little distance above the ledge to allow the chalk-dust 25 to fall through. The wires are connected to the end bearings by screw-bolts c c, by which means the wires can be drawn taut. In cross-section the wires are located in concave form, so as to hold the erasers more effectively when 30 placed thereon.

35 D is the carrier which runs on the wires. It consists of an exterior open frame d, provided with small tubular bearings g g g, which slide on the wires, and an interior open-topped box or receptacle f, which holds the crayons. This box is removable, so that it can be cleaned 40 of dust at any time.

The parallel wires above described serve as a surface on which to scrape and clean erasers,

the chalk-dust falling through to the ledge 50 below. The spaces between the wires, being unimpeded, allow free passage of the dust, and are more effective than the wire screen or network heretofore used. At the same time these wires furnish a track for the passage of the 55 carrier from end to end of the blackboard, or over a given section of its length if the blackboard is very long.

The carrier serves not only as a holder of the crayons to enable them to be moved from 60 one end to the other to be within easy reach of the user, but it also serves as a cleaner of the wires, the tubes g g g being of such length as to cover considerable space of the wires. The wires are thus kept clean by the constant motion of the carrier in being slid from 65 one end to the other, and it prevents the soiling of clothing, which occurs where fine dust gathers thereon. The three wires form a broad surface on which erasers can be readily 70 cleaned.

Having described my invention, I do not claim a wire net at the bottom of the blackboard.

What I claim as new, and desire to secure 75 by Letters Patent, is—

1. In a blackboard, the combination of the parallel wires a a a, forming a cleaning-surface and a track, and the carrier D, provided with tubular bearings g g g, running thereon, 80 forming a crayon-holder and wire-cleaner, as herein shown and described.

2. In a blackboard, the combination of three parallel wires a a a, the bearings b b, to which they are attached, the screw-bolts c c for 85 straining the wires, the carrier-frame d, provided with the tubular bearings g g g, running on the wires, and the removable box f, resting in the frame, as shown and described, and for the purpose specified.

In witness whereof I have hereunto signed my name in the presence of two subscribing witnesses.

JOHN W. HUNGAD.

Witnesses:

R. F. OSGOOD,
WM. J. MCPHERSON.
